CLAIM

The ornamental design for a jewelry setting, as shown and described.

DESCRIPTION

FIG. 1 is a front perspective view of a jewelry setting illustrating the new design;

FIG. 2 is a rear perspective view of the jewelry setting illustrated in FIG. 1;

FIG. 3 is a top view of the jewelry setting illustrated in FIG. 1;
FIG. 4 is a bottom view of the jewelry setting illustrated in FIG. 1; and,

FIG. 5 is a right side elevational view of the jewelry setting illustrated in FIG. 1 (the left side elevational view is a mirror image of FIG. 5).
